LOCOMOTIVE STEAM CUT-OFF CONTROL
MEANSEarl E. Chapman and Howard H. Lanning,
Topeka, Kans.

Application November 7, 1931, Serial No. 573,560

4 Claims. (Cl. 121—142)

Our invention relates more particularly to a steam cut-off control for locomotives whereby a novel limited cut-off starting valve arrangement is provided.

The invention has for its object the provision of means adapted to admit additional steam to the cylinders of the locomotive, after the main cut-off has been effected, for the purpose of providing additional power in moving the cylinder piston to the limit of its stroke; in other words, the purpose of our invention is to maintain full steam pressure in the cylinder after the main steam admitting port has been cut off, while at the same time preventing excessive pre-admission of steam to the cylinder.

The objects and advantages of our invention will be readily comprehended from the detailed description of the particular exemplification of the invention which may have expression in modified embodiments.

In the drawings:—

Figure 1 is a longitudinal sectional view of a locomotive steam chest and its piston-valve and a portion of a cylinder and its piston, with our improved means associated therewith; one part of said means being in section while the other part is in elevation; the operating medium conveying pipes being broken away.

Figure 2 is a side elevation of the locomotive reverse lever provided with our improved means, and showing portions of the operating medium conveying pipes with a portion shown in section.

Figure 3 is an end elevation of the mechanism shown in Figure 2 with a portion broken away.

Figure 4 illustrates, in side elevation, an arrangement of air pipes and valves for manual control.

Figure 5 is a detail sectional view of the hand operated valve shown in Figure 4, illustrating the valve condition when the hand lever is in the position shown in Figure 4.

Figure 6 is a similar view showing valve condition when the hand lever is at an intermediate or vertical position.

Figure 7 is a similar view showing the valve condition when the hand lever is in the opposite position from that shown in Figure 4.

Figure 8 is a diagrammatic view illustrating the reverse lever automatic control of the starting valves, with the pressure medium pipes.

Figure 9 is a similar view illustrating a modification involving booster mechanism and manual control whereby the starting valves may be actuated independently of the reverse lever.

Our invention relates to means whereby addi-

tional steam is admitted to the cylinder after the main steam port has been cut off or closed by the piston-valve in the steam chest, in order to provide additional power for moving the cylinder piston to the limit of its stroke, or to maintain full steam pressure in the cylinder after the main steam admitting port has been closed or cut off,—a condition especially desirable when the locomotive is starting or moving a heavy train at slow speed,—while at the same time providing means which prevents excessive pre-admission of steam.

The invention, as exemplified in the drawings, is shown applied to a well known type of locomotive steam chest or chamber indicated at 10, associated with the cylinder of which only a portion is shown at 11.

The steam chest 10, at an intermediate point, is provided with the usual steam receiving inlet as at 12; and steam passages or ports between the steam chest and the opposite ends of the cylinder are shown at 13, 14.

The steam chest 10, to opposite sides of the inlet, is provided with the usual sleeves or valve cages 15, 15, having the usual circumferentially arranged ports 16 communicating with steam passages in the wall of the steam chest and which in turn connect with the passages or ports 13, 14 leading to opposite ends of the cylinder 11. A well known type of double piston slide valve is shown at 17, for controlling passage of steam from the intermediate steam incoming portion of the steam chest to the main steam ports 16 and hence to ports 13, 14. The opposite ends of the steam chest or chamber 10, are, of course, provided with the usual exhaust channels at 18.

The valve cages 15, at a predetermined point intermediate of the main ports 16 and the inner ends of the cages, are provided with auxiliary ports 19, which communicate with the passages 20 in the wall of the steam chest. The relation between the ports 16 and 19 and the width of the heads of piston valve 17 is such that the main ports 16 will be cut off before the steam edges of the valve-heads reach the auxiliary ports 19 during the return stroke of the valve 17 toward the opposite end of the steam chamber 10.

The steam chest or chamber 10, at opposite ends, is provided with a chambered housing 21, provided in its bottom with a steam inlet port 22 arranged in steam tight communication with each steam passage 20 in the steam chest wall. One chamber 23 of each housing 21 is provided with a valve 24, adapted to close in the direction of flow of steam through port 22; the valve 24,

at the left in Figure 1, being shown depressed off its seat 25, thus allowing steam to flow into chamber 23 from the steam chest 10 while the piston-valve 17 is in the position shown in Figure 1.

- 5 Chamber 23 of each housing 21 has a suitable outlet pipe 26 which leads down toward the cylinder and is suitably formed and connected with a port 27 in the wall of the cylinder 11. A port 27 is provided in each end of the cylinder at a 10 predetermined distance from the main steam passages 13, 14; and these ports 27 in turn communicate with the small ports 28 in the cylinder liner or bushing 29 with which the bull-rings of the piston 30 having sliding steam-tight relation.
- 15 The valve 24, which is preferably shown somewhat in the nature of a poppet type of valve, is controlled or depressed by means of the bell-crank lever 31 suitably mounted in the housing 21 with its one end shown disposed upwardly and pivotally secured to the stem 32 of a slideable valve 33 mounted in the chamber 34 of the housing 21. The valve 33 is held in its normal position by the action of spring 35; the valve 33, at the left in Figure 1, being shown in its actuated position 25 induced by the air pressure in chamber 34.

The chamber 34 has a minute port 36 which communicates with pipe 37 which leads to an air valve casing 38 shown in Figures 2, 3 and 4. The valve casing 38 is of a well known type provided with what is known as a pilot valve shown at 39 in Figure 2; the casing being also provided with the usual small air "bleeding" port at 38a. In view of auxiliary steam conveying and controlling means at both the ends of the steam chamber, 30 it will be understood that the pipe 37 leading from valve casing 38 (see Figure 4) at its other end has two branches leading to the two air chambers 34 as shown in Figure 1.

This valve casing is suitably mounted adjacent to the lower end of the usual locomotive reverse lever 40; and the valve casing 38 has a pipe 41 connected with the main air reservoir A on the locomotive.

Mounted adjacent to valve casing 38 is a floating or vertically oscillatable lever 42, fulcrumed at 43; with the long depending arm of the lever 42 positioned so as to normally be in contact with and adapted to actuate or depress the stem 39 of the air pilot valve located in valve casing 38. The lever 42 is also provided with an upstanding arm 42a above the fulcrum point of the lever; and also preferably provided with an arm 42b extending laterally from the lever and adapted to contact with a suitable stop lug, as at 44, to 55 prevent the too far outward swing or movement of the lever, namely to the right as viewed in Figure 2.

Associated with the reverse lever 40, so as to move therewith, is the floating lever controlling 60 means shown provided with arms 45 and 46. In the particular embodiment disclosed in the drawings, this means is shown comprising a hub portion 47 secured to the reverse lever 40.

The arms 45 and 46 are shown integral with the reverse lever 40, so as to cause said arms to move with reverse lever 40.

As is apparent from the construction shown in Figure 2, when reverse lever 40 is moved to the left, arm 45 will contact with short arm 42a of the floating lever 42 and cause the lower end of said lever to actuate stem 39 of the pilot valve in the casing 38; while movement of the reverse lever 40 to the right will move arm 45 away from the short arm 42a and cause arm 46 to engage 75 the lower end of the floating lever 42 and force

the latter into operating relation with the stem 39 of the pilot valve in casing 38.

As the air pilot valve may be of a well known construction at present in use, detailed description thereof is not deemed necessary; it being understood that the pilot valve is normally held on its seat so as to prevent passage of compressed air from supply pipe 41 through the casing 38 and into pipe 37 by means of the spring shown at 39a.

The piston 30 is shown at an intermediate point in cylinder 11 and is assumed to be moving toward the right in Figure 1, with the piston-valve 17 in the steam chamber having traveled sufficiently toward the right where it has closed off steam admission through the main steam port 16 at the left of the steam chamber 10, while the auxiliary port 19 at said end is still in steam admitting condition; the main port 16 and auxiliary port 19 at 15 the right hand end of the steam chamber 10 being closed by the piston valve 17 against steam admission.

When reverse lever 40 is placed in either extreme forward or extreme backward position, the air valve in casing 38 will be opened by means of 25 arm 46 or arm 45, which in turn actuate lever 42 so as to engage the air valve-stem 39. When this air valve is open compressed air from the main air reservoir of the locomotive will flow through pipe 37 into air chamber 34. The compressed air entering chamber 34 will force piston 33 against the action of spring 35, causing lever 31 to be rocked on its fulcrum point, which in turn will force valve 24 downwardly off its seat and permit steam to flow from port 28 into chambers 23 and 30 35 thence into auxiliary steam pipe 26, as shown at the left in Figure 1.

When reverse lever 40 is moved a suitable distance away from either of its extreme positions, the air valve 39 will close (the valve being usually provided with a spring for normally moving 40 it toward its seat) and shut off supply of compressed air to pipe 37, allowing the air contained in pipe 37 and chamber 34 to exhaust through a minute "bleeding" or vent port 38a. The spring 35 will then cause piston 33 to move toward the 45 left in Figure 1, back to normal position, thereby rocking bell-crank lever 31 upwardly, which in turn will pull valve 24 upwardly to its seat, thereby cutting off admission of steam into chamber 23 and into pipe 26.

In other words, the starting means is put into operation by the opening of the valve 24 at opposite ends of the steam chamber; it being understood that the construction and operation of the means at the right of the steam chamber is identical with that shown in section at the left and as heretofore described; the mechanism at the left being operative when the piston valve 17 is at the left hand end of the steam chamber, and the reverse lever 40 is in one of its extreme positions, 50 while the mechanism at the right comes into play when the piston valve 17 is at the right-hand end of the steam chamber and the reverse lever is in one of its extreme positions.

In the drawings, it is assumed that either arm 65 45 or arm 46 is in the dotted line position shown in Figure 2, thus admitting air through air valve 39 into both pipes 37 and chambers 34 of the chambered housings 21 at both ends of the steam chamber 10. Therefore, the valve 24 in both 70 housings 21 have been moved or depressed off their seats 25 so as to establish communication between the steam ports 20 in the wall of the steam chamber 10 and the two pipes 26 leading to opposite ends of the cylinder 11. In Figure 1 we 75

have shown the piston 30 in full lines in one phase of its operation and in dotted lines in another phase of its operation, but for clarity in the drawings have not endeavored to show different phases 5 of piston-valve operation or positions.

It is understood, however, that the operations of the piston-valve 17, piston 30 and the locations of auxiliary ports 19 and ports 27-28 are so correlated that admission of steam through ports 10 27-28 takes place at either one end or the other, after the piston has traveled in its return stroke toward the opposite end of the cylinder far enough to uncover the adjacent port 28 and valve 17 has traveled sufficiently to admit steam 15 through the complementary auxiliary port 19.

In Figure 1, piston 30 in the dotted lines and the valve 17 are both moving toward the back limit of their respective travels; the valve 17 having uncovered auxiliary port 19 at the left while 20 main port 16 at the left is still covered or shut off. Live steam therefore may enter said auxiliary port 19 and fill the associated pipe 26 and port 27. The steam, however, is prevented from 25 entering the cylinder 11 because port 28 is covered by the piston 30. This arrangement of ports is quite essential, particularly when auxiliary ports of large area are employed, as steam admitted to the back end of the cylinder when the piston is moving toward the end of its travel 30 would cause what is commonly termed "excessive preadmission" and would seriously interfere with the normal movement of the piston.

The piston 30 in full line position is moving toward the forward limit of travel. The piston-valve 17 at this time is also presumed to be moving toward the right in Figure 1, having closed off main port 16 (after having been opened for steam admission in the usual manner) but not sufficiently to close off the associated auxiliary 35 port 19, and, of course, not sufficiently to open the ports at the right hand end of the steam chamber. With the auxiliary port 19 still open, live steam may flow through this port, through chamber 23 (valve 22 being open) into pipe 26, 40 through ports 27-28, into the back end of the cylinder 11, thus maintaining steam pressure behind the piston 30 after the main steam port 16 has been closed or covered by the steam valve 17.

This function of our improved means, namely admitting steam after the main steam ports have been closed, is desirable in starting the locomotive or when moving a heavy load at very slow speed. It is not desirable, however, at ordinary speeds, and therefore we have devised 50 our improved means so as to be operable only when the reverse lever 40 has been placed in either of its extreme positions, positions which are not assumed in the ordinary running speed of the locomotive. Hence, valves 24 will be closed 55 during the ordinary or normal operation of the locomotive, as reverse lever 40 is kept in its extreme forward or backward position only when the locomotive is starting a train or moving very slowly.

Consequently, by reason of our improved means and its arrangement, the appropriate manipulation of the reverse lever 40 causes the respective valves 24 to be operated in accordance with the best practice without necessitating extra effort 60 or attention on the part of the enginemen.

It is understood, of course, that a similar condition obtains at the right of the steam chamber and cylinder during the reciprocating movements 70 of the piston-valve 17 and piston 30, when the

reverse lever 40 is in one of its extreme positions.

We have described the exemplification of our invention, shown in the first three figures of the drawings, wherein the pneumatically operated starting valves of our limited cut-off arrangement are designed so that under normal operating conditions the starting valves will open automatically when the reverse lever 40 is placed in either of its extreme positions. 10

Our improved system or means is also designed so that the starting valves may be manually controlled by the enginemen independently of the reverse lever if desired. The arrangement of pipes and valves, whereby this may be accomplished, is shown in Figures 4 to 7, inclusive. 15

During both automatic and manual operations, compressed air is admitted to the system through the pipe 41.

Where the locomotive is provided with a booster, compressed air for coordinating the actions of the starting valves with those of the booster is obtained from the pneumatic control system of the booster through the pipe 48 which is provided with a non-return check valve at 49 in order to 20 prevent back flow of compressed air through the cock or valve 50 and pipe 48. The pipe arrangement and valve 50, which is provided with hand lever 51, enables manual operation of the starting valves as well as coordination of the action 25 between the starting valves and the booster (if one is employed). The valve 50 receives compressed air from pipe 41 by the pipe 52 while the opposite side of the valve or cock is provided with a pipe 53 which is shown connected 30 by means of pipe 54 with pipe 37 on one side of the locomotive and connected by means of pipe 54a with the air chambers 34 located on the opposite sides of the locomotive and in manner similar to pipe 37, whereby compressed air 40 is admitted into all of the air chambers 34 on both sides of the locomotive as previously described.

With the valve or cock 50, namely with its hand lever 51 in the position shown in Figures 4 and 5, 45 our improved means is shown in normal running position, thus enabling the starting valves to open automatically when the reverse lever 40 is placed in either of its extreme positions, or when the booster (if one is employed) is cut in 50 by means of a suitable valve as shown in Figure 4 by booster operating valve *a*. The starting valves will also close automatically, as previously described, when the reverse lever is placed to running position or when the booster (if one 55 is used) is cut out by closing booster operating valve *a*.

Assuming the reverse lever 40 to be at or near its central position (and the booster not in operation), compressed air in the locomotive main 60 reservoir would be present in pipes 41 and 52 and would be retained therein by the valve or cock 50 when the latter is in the position shown in Figures 4 and 5 and the air would also be held by the valve 38 (which is normally closed). 65 The air in pipe 48 would be at atmospheric pressure with the booster not in operation. If the reverse lever 40 should then be moved to either of its extreme positions, the valve 38 would be unseated, exhaust or vent port 38a will be closed 70 by the stem 39 of valve 38 and compressed air would flow from pipe 41 through valve body 38 in the manner heretofore described. When the reverse lever 40 is moved away from an extreme position, valve 38 is restored to its seat and 75

the exhaust or vent port 38^a is opened causing the air to exhaust from pipe 37 and chamber 34 by means of port 36 and allowing spring 35 to force the piston 33 to normal position, thereby 5 rocking bell-crank lever 31 and lifting valve 24 to its seat, the air in pipes 54 and 37 exhausting through the port 38^a.

Locomotive boosters are operated by a pneumatic control system devised therefore; the booster 10 being placed in operation by the admission of compressed air from the locomotive main air reservoir as shown at A in Figure 4 into the booster control system and the booster is cut out by exhausting the air from its control system by 15 a suitable vent opening in the booster control valve.

On a booster type of locomotive, with the valve 50 in the position shown in Figures 4 and 5, the starting valves would open automatically when 20 the booster is cut in by opening valve *a*, located in pipe 58, connected with pipe 41, and having connection with pipe 57 which is connected by pipe 56 with pipe 48, because the compressed air reaches the starting valve cylinders from the 25 booster control system by passing through pipe 48 and into pipes 53 and 54^a. When the booster is cut out, the supply of air through pipe 48 will also be cut off and air from the starting valve cylinder would be exhausted through the re- 30 stricted vent port 38^a of the valve 38. If a quicker closing of the starting valve is desired, the handle 51 of valve or cock 50 may be moved to the position indicated in Figure 6 which places the valve in the position shown in said figure, thereby al- 35 lowing air from pipes 53, 54 and 37 to exhaust through the vent port 55 shown in Figure 6 ar- ranged in the valve 50; this vent port acting in addition to the vent port 38^a as previously de- scribed.

40 If it is desired to manually open the starting valves heretofore described at any time independently of the reverse lever and locomotive booster (if one is employed), this may be accomplished by proper manipulation of the handle 45 51 of valve or cock 50, by moving the handle 51 to the position shown in Figure 7, thereby allowing air from pipe 41 and pipe 52 to pass through the valve 50 into pipe 53 and into pipe 54^a which is connected with the respective chambers 34 on 50 the opposite sides of the locomotive. The start- 55 ing valves would then open irrespective of the reverse lever position or regardless of whether the locomotive booster is cut in or out.

By moving handle 51 of valve or cock 50 to the 55 position shown in Figure 6, air will be exhausted from the operating cylinders through vent ports 38^a or 55 or both when the starting valves will immediately close.

It is desirable to have the starting valves open 60 at all times when the locomotive is working under conditions which necessitate placing or keeping the reverse lever in either of its extreme forward or backward positions. Consequently no provi- 65 sion is made for forestalling the automatic open- ing of the starting valves when the reverse lever is in either of its extreme positions. It is sim- 70 ilarly desirable to keep the starting valves open when the booster is in operation, although the booster may be used for short periods of time at speeds above those which call for extreme full gear position of the reverse lever. The arrange- 75 ment is therefore made so that starting valves will open automatically when the booster is cut in, but with the starting valves open under con- ditions of booster operation and with the reverse

lever removed from its extreme position, the vent port 38^a will discharge air continuously from pipe 54 as long as the starting valve cylinders are receiving air from the booster control system. This discharge of air warns the engineer and prevents him from overlooking the duty of closing the starting valves promptly when the necessity for their use is past, the closing operation being performed by moving the handle 51 of cock 50 into the position shown in Figure 6.

Vent port 55 sounds a similar warning if the handle of cock 50 is inadvertently left in the position shown in Figure 6 and allowed to remain in that position when the reverse lever is again placed in either of its extreme positions. This 15 warning reminds the engineer of his duty to maintain the handle of cock 50 in position shown in Figures 4 and 5 at all times except when service conditions require it to be in other positions.

It is obvious that on a locomotive which is not 20 equipped with a booster and where manual operation of the starting valves is not contemplated, that cock 50, the booster operating valve *a*, pipes 48, 52, 53, 56, 57 and 58 and the booster cylinder mechanism, as shown in Figure 4, are not needed 25 and may be omitted; while pipes 54 and 54^a with its bifurcated end then in reality are made as continuations of pipe 37 to connect with both starting valves on each side of the locomotive, as previously described.

We have shown desirable embodiments of our invention, which have been described in terms employed merely as terms of description and not as terms of limitation, as structural modifications may be made without, however, departing from 35 the spirit of our invention.

What we claim is:—

1. In a locomotive provided with cylinders, steam chests, a reverse lever and a fixed pivot point for the lever, the combination of auxiliary steam admission ports at opposite ends of the cylinders; independent steam conveying conduits intermediate of points in the steam chests controlled by the main valve in said chests and the said auxiliary ports at opposite ends of the cylinders; a valve in each of said conduits for controlling passage of steam to the auxiliary ports of the cylinders when the main valves of the steam chests are in predetermined positions; separate air operated means for separately controlling the valves in said conduits; a compressed air supply for said air operated means; a normally closed valve located adjacent to said reverse lever for controlling the flow of compressed air to said air operated means; a loosely pivoted member disposed beneath the reverse lever with one end ar- 55 ranged in operative relation with said normally closed valve; and a pair of depending arms associated with the reverse lever and extending to opposite sides of the vertical plane of the pivot point of the reverse lever, each arm being adapted to actuate said loosely pivoted member when the reverse lever is moved to either one of its extreme positions.

2. In a locomotive provided with a reverse lever, a pivot point for said lever, cylinders, and steam 65 chambers provided with piston valves and main steam ports at opposite ends controlled by said piston valves; the combination of auxiliary steam ports in said steam chambers at opposite ends adjacent to the main steam ports, said auxiliary 70 steam ports being controlled by said piston valves; auxiliary steam admitting ports at opposite ends of the cylinders; steam conveying conduits intermediate of the respective auxiliary ports at the same ends of the steam chambers and the 75

cylinders; a valve in each of said conduits closable in the direction of flow of steam through said conduits; air operated means for controlling said last valves; a compressed air supply line for said air operated means provided with a self-closing valve disposed adjacent the fulcrum point of the reverse lever; movably mounted means beneath the reverse lever for actuating said self-closing valve; and bifurcated means associated with the reverse lever and extending to opposite sides of the pivot point of said lever, with the bifurcations of said means adapted to actuate the movably mounted means when the reverse lever is moved into either one of its extreme positions.

3. In a locomotive provided with a reverse lever, cylinders provided with pistons, and steam chambers provided with piston valves and main steam ports at opposite ends communicating with opposite ends of the cylinders; the combination of auxiliary ports in said steam chambers adjacent said main ports and controlled by said piston valves; auxiliary steam admitting ports adjacent the ends of the cylinders and closable by the pistons of the cylinders; separate steam conveying conduits intermediate of the auxiliary ports at the corresponding ends of the steam chambers and the cylinders adapted to admit an auxiliary steam supply to the cylinders after the pistons are on their return strokes; normally closed valves in said conduits for controlling the flow of steam therethrough; pressure medium operated means for opening said normally closed valves; a pressure medium supply line communicating with said last mentioned means and provided with a normally closed pilot valve disposed adjacent to the reverse lever; a member pivoted intermediate of its end and arranged beneath the reverse lever with one end thereof adapted to engage the pilot valve to open same; and a bifurcated lever operatively associated with the reverse lever, the bifurcations of the lever being adapted to engage with opposite sides of one end of said

pivoted member and thereby force the other end of said pivoted member into valve operating position when the reverse lever is moved into an extreme forward or extreme backward position.

4. In a locomotive provided with a reverse lever, steam chests provided with piston valves, and cylinders provided with pistons; the combination of auxiliary steam ports adjacent opposite ends of the steam chests and controlled by said piston valves; auxiliary steam ports adjacent opposite ends of the cylinders and closable by the pistons; separate steam conduits intermediate of the auxiliary ports at the corresponding ends of the steam chests and of the cylinders whereby auxiliary steam supplies to opposite ends of the cylinders may be provided; normally closed valves in said conduits for controlling the flow of steam therethrough; housings, each provided with a spring controlled piston operable by a pressure medium; bell-crank levers intermediate of the spring controlled pistons in the housings and the valves in said auxiliary steam conduits; pressure medium supply lines connected with said housings and with a main pressure medium supply line; a normally closed valve in said pressure medium supply line arranged adjacent the fulcrum point of the reverse lever; a member pivoted intermediate of its ends with one end in operative relation with said last mentioned normally closed valve; a pair of arms depending from the fulcrum point of the reverse lever and adapted to engage one end of said pivoted member when the reverse lever is moved to either one of its extreme positions whereby said last mentioned normally closed valve is opened, pressure medium admitted to said housings, the spring controlled pistons actuated and said bell-crank levers tilted so as to open the normally closed valves in the auxiliary steam conduits and thereby admit an auxiliary steam supply to the cylinders.
